DESK

Robert U. Rourke, P.O. Box 1,
Pomfret Center, Conn. 06259

Filed Feb. 7, 1966, Ser. No. 931

Term of patent 14 years

(Cl. D33—7)

FIG. 1

FIG. 2

FIG. 3

FIG. 4

FIG. 5

FIG. 1 is a perspective view of the novel desk of my new design shown with a conventional base in broken lines for illustrative purposes only.

FIG. 2 is a top plan view thereof.

FIG. 3 is an elevational side view thereof.

FIG. 4 is an elevational front view thereof.

FIG. 5 is an elevational rear view of my novel desk. The dominant features of my design reside in those portions shown in full lines on the drawing.

I claim:

The ornamental design for a desk, as shown and described.
